US0D1058539S

(12) **United States Design Patent** (10) **Patent No.:** **US D1,058,539 S**
(45) **Date of Patent:** ** *Jan. 21, 2025

(54) **EARPHONE**

(71) Applicant: **Flare Audio Technologies Limited**,
Lancing (GB)

(72) Inventor: **Davies Roberts**, Lancing (GB)

(73) Assignee: **FLARE AUDIO TECHNOLOGIES
LIMITED**, Lancing (GB)

(*) Notice: This patent is subject to a terminal disclaimer.

(**) Term: **15 Years**

(21) Appl. No.: **29/751,611**

(22) Filed: **Sep. 22, 2020**

(30) **Foreign Application Priority Data**

Mar. 23, 2020 (GB) 6085879
Sep. 18, 2020 (GB) 6100942
Sep. 18, 2020 (GB) 6100943
Sep. 18, 2020 (GB) 6100944

(51) **LOC (15) Cl.** **14-01**

(52) **U.S. Cl.** **D14/223**

(57) **CLAIM**

The ornamental design for an earphone as shown and described.

DESCRIPTION

FIG. 1 is a front perspective view of an earphone, showing my new design;

FIG. 2 is a top plan view thereof;

FIG. 3 is a rear perspective view thereof;

FIG. 4 is a front elevation view thereof;

FIG. 5 is a side elevation view thereof;

FIG. 6 is a rear elevation view thereof; and,

FIG. 7 is a bottom plan view thereof.

In the drawings, the broken lines depict portions of the earphone that form no part of the claimed design.
